UNITED STATES PATENT OFFICE.

SABIN HUTCHINGS AND JOSEPH D. LEACH, OF PENOBCOT, MAINE.

CHURN.

Specification of Letters Patent No. 29,597, dated August 14, 1860.

To all whom it may concern:

Be it known that we, SABIN HUTCHINGS and JOSEPH D. LEACH, of Penobscot, in the county of Hancock and State of Maine, have 5 invented a new and useful Improvement in Churns and also an Improved Method of Operating Our Improved Churn in Connection with other Things Appertaining to a Dairy; and we do hereby declare that the following is a full and exact description thereof, reference being had to the accompanying drawings, which form a portion of this specification.

In all dairy establishments, a sink and a 15 pump are required to be in convenient proximity to the churn; and bearing this fact in mind, we have arranged a place for our churn C, at one end of the sink B, and have secured a pump D, to the bottom of said sink, while we have located the shafts r, and 20 t, of the driving wheels e, and f, in a box immediately beneath the sink B, so that a single actuating lever k, can be jointed to the dasher-rod m, of the churn, the valve- 25 rod l, of the pump, the pitman g, which rises through the bottom of the sink from the crank-shaft t, and also to the standard i, which rises from one end of the sink. The crank-shaft t, carries the fly-wheel p, and 30 the toothed-wheel f. The driving shaft r, which is actuated by means of the crank h, is connected to the toothed-wheel f, on the

crank-shaft t, by means of the toothed-wheel e.

The dasher of the churn C, may be operated independently of the pump, and the pump may be operated independently of the churn, as circumstances may require.

The cover of the churn has a large central aperture through which the dasher-rod plays, and this aperture has a funnel-shaped curve s, rising from its periphery which prevents any waste of cream, while the size of the aperture which it incloses, allows the air to freely enter the body of the churn and 45 perform its legitimate assistance in the churning process.

What we claim as our invention, and desire to secure by Letters Patent, is—

The arrangement of the churn C, the 50 pump D, the sink B, the lever k, the pitman g, the actuating shafts r, and t, the toothed-wheels e, and f, and the hand-crank h, substantially in the manner and for the purpose herein set forth.

The above specification of our improvement in churns, &c. signed and witnessed this twenty-sixth day of June, 1860.

SABIN HUTCHINGS.
JOSEPH D. LEACH.
